RUDOLPH VOLLSCHWITZ, OF NEW YORK, N. Y., ASSIGNOR TO HIMSELF
AND J. J. SCHLAEPFER, OF SAME PLACE.

Letters Patent No. 60,970, dated January 1, 1867.

IMPROVEMENT IN DOOR LOCKS.

The Schedule referred to in these Letters Patent and making part of the same.

TO ALL WHOM IT MAY CONCERN:

Be it known that I, RUDOLPH VOLLSCHWITZ, of the city, county, and State of New York, have invented a new and useful Improvement in Locks; and I do hereby declare that the following is a full, clear, and exact description thereof, which will enable others skilled in the art to make and use the same, reference being had to the accompanying drawing, forming part of this specification, in which—

Figure 1 represents an elevation of this invention, one-half of the case having been removed to expose the internal mechanism.

Figure 2 is a similar view, the tumblers having been removed to expose the parts below.

Figure 3 is a transverse section of the same, the line $z z$, fig. 1, indicating the plane of section.

Figures 4, 5, and 6 are detached views of the tumbler.

Similar letters of reference indicate like parts.

This invention relates to a lock, the mechanism of which is enclosed in a cylindrical case; said mechanism being composed of three (more or less) tumblers, which are provided with slots to admit the key, so that by turning said key the heads of the tumblers arrange themselves in the proper position to allow the bolt to move in or out. An elastic pad or spring, which bears on the ends of the several tumblers, has a tendency to keep the same in such a position that their slots coincide to admit the key, and that their heads prevent the bolt from moving, the whole mechanism being so arranged that it takes but little room, and that a safe lock with a small and convenient key can be produced at a comparatively small cost.

A represents a tubular or cylindrical case, which is secured to the face-plate B, and which encloses the mechanism of my lock. C is the bolt, the head of which is fitted in a square mortise in the face-plate of the lock in the usual manner. The shank of this bolt extends back in the case, and from its surface rise three lugs, $a a b$, two on one side of the key-hole c and one behind, as shown particularly in fig. 2 of the drawing. The lugs $a a$ are arranged one opposite the other, or they may be placed in any convenient position, and they form the abutments for the shoulder $d d'$ on the tumblers D. These tumblers are secured to a pivot e near the rear end of the case, and their ends bear against a block, f , of India rubber, or of any other elastic material, whereby said tumblers are brought in such a position that their shoulders catch over the edges of the lugs $a a$, in front or behind, according to the position of the bolt, and the motion of said bolt is rendered impossible until all the tumblers are brought in such a position that their shoulders clear the lugs $a a$. This purpose is effected by the action of a key, K, the bit of which extends in the direction of its shank, and is equal in width to the diameter of said shank, so that it can be conveniently carried in the pocket. Said bit is introduced through the key-hole c in the case or in the nut from either side, and it passes through mortises g in the tumblers, which are so arranged that in turning the key the notched edges of the bit act on the inner edges of said mortises, and thereby the tumblers are brought in such a position that the shoulders $d d'$ clear the lugs $a a$, and the bolt is free to move in or out. The motion of the bolt is effected by the action of a nut, E, which is situated between the tumblers and the shank of the bolt, and which is provided with two wings $h h$ that act on the lug b , one to push the bolt out and the other to push the bolt in. Said nut revolves freely in the case A, and it is provided with a hole to admit the bit of the key. This hole corresponds to the key-hole c in the case, and when the key is inserted in the nut and turned the tumblers are made to release the bolt, and then one of the wings $h h$ acts on the lug b and moves the bolt in or out as the case may be. The barrel of the nut is flattened and subjected to the action of a spring, i , which has a tendency to hold the nut in position when the bolt is in or out, and to carry the nut back to that position whenever it is turned.

By these means a lock is produced, the mechanism of which takes up but little room, and with three or more tumblers, rendering the same safe against burglars; and, furthermore, the key is so shaped that it can be conveniently carried in the pocket.

What I claim as new, and desire to secure by Letters Patent, is—

The mortises g in the tumblers D to operate in combination with the flat-notched bit of the key, nuts E, and bolt C, substantially as and for the purpose described.

RUDOLPH VOLLSCHWITZ.
